CONCRETE BLOCK MAKING MACHINE

Frederick W. Pfeifer, West Allis, Wis.

Application April 27, 1936, Serial No. 76,642

31 Claims. (Cl. 25—41)

This invention relates to a method of manufacturing concrete building blocks, and to a machine for practicing the method.

In attempts to manufacture concrete blocks from light weight material such as slag or cinder concrete, it has been common practice to tamp or press the material in the mold. Such tamping fractures the light, porous aggregate in the concrete adjacent the tamper. The surfaces fractured are not coated with cement, and hence are not cemented together when the concrete sets. The result is that if the blows of the tamper are severe enough to properly tamp the concrete at the bottom of the mold, the concrete at the top 10 will be so fractured as to crumble readily. If less pressure is exerted in the tamping, that portion of the block adjacent the tamper is well tamped, but the density of the block diminishes as the distance from the tamper increases. The 20 result of light tamping is, therefore, a block which is properly tamped adjacent the tamper but which has other parts soft and crumbly.

The present invention has as one object the production of a light weight concrete block of even texture.

Another object is to devise a method of forming light weight concrete blocks in which breakage of the fragile aggregate is avoided.

Another object is to devise a method of forming light weight concrete blocks in which all parts of the blocks are subjected to substantially the same tamping pressure.

A further object is to produce a machine to form blocks of light weight concrete which will exert a uniform tamping pressure throughout the depth of the blocks.

A further object is to produce a machine to form blocks of light weight concrete having even texture.

40 A further object is to produce a block forming machine which will mold light weight concrete blocks without breaking the aggregate during molding.

A further object is to produce a block forming machine to mold concrete blocks in which packing of the concrete is done by vibration, and in which the concrete is maintained above the top surface of the block during the forming operation.

50 Another object of the invention is to produce a machine to form light weight concrete blocks with holes therethrough, the machine including an improved core mounting and actuating mechanism.

55 A still further object is to produce a block

forming machine to mold light weight concrete blocks in which excess material is removed from the top of the block after suitable tamping and is used in the formation of the next block.

The method of forming light weight concrete blocks comprises, filling a block mold with concrete, maintaining the level of the concrete above the top of the mold, and subjecting the mold and concrete to vibration to tamp the concrete.

The machine used to accomplish this method 10 includes a mold mounted on a vibrating table, and a hopper above the mold adapted to vibrate therewith while maintaining the minimum level of the concrete above the top of the mold.

The invention further comprises, in combination 15 with the jarring table and the mold, cores which project horizontally into the molds through the vertical ends of the molds.

The invention also comprises a pair of knives which are adapted to pass between the mold and the hopper to cut off the concrete at the top of the mold and form a bottom for the hopper.

A specific example of such a machine is shown in the accompanying drawings and described in the following specification. In the drawings:

Fig. 1 is a front elevation of the machine with the cores in place;

Fig. 2 is a top view of the machine with the cores withdrawn;

Fig. 3 is a horizontal section through the mold 30 with the cores in place;

Fig. 4 is an end view of the machine with the hoppers in raised position and the molds on their sides, preparatory to removing blocks from the molds;

Fig. 5 is a cross-section on the line 5—5 of Fig. 2, with the molds in working position and the hoppers raised;

Fig. 6 is a cross-section on the line 6—6 of Fig. 2, showing the cores withdrawn from the 40 molds;

Fig. 7 is a detail showing the cradles for carrying the hoppers and the cut-off knives;

Fig. 8 is a cross-section on the line 8—8 of Fig. 5, looking in the direction of the arrows; 45 and

Fig. 9 is a detail of the cradle latch and release.

Referring to the drawings, in which like numbers indicate like parts throughout the several views, the machine is built on a frame generally designated 15, which may comprise a base 16, four posts 17, and suitable cross braces 18 between the posts.

The base 16 includes a pair of I-beams 20 55

which support a cylinder jacket 21. The jacket 21 has a vent port 22 to permit the escape of air therefrom. A cylinder 23 is mounted within the jacket 21. A piston 24 operates in the cylinder 23, and has an extension or collar 25 of enlarged diameter which rests on the top of the jacket 21 to prevent the bottom of the piston from striking the bottom of the cylinder.

An air conduit 26 is formed in the piston and leads from a valve-controlled air hose 27 through the collar 25 to a point on the side of the piston adjacent the side wall of the cylinder 23. When the piston is in its lowermost position, as shown in Fig. 6, the lower end of the conduit 26 opens 10 into a conduit 28 in the side of the cylinder 23, which, in turn opens into the space below the piston. A port 29 vents the compressed air trapped below the piston when the piston rises above the port.

20 The lower end of the piston is recessed to trap a comparatively large quantity of compressed air before the piston 24 has time to move the conduits 26 and 28 out of engagement. Thus when compressed air is admitted through the 25 hose 27 it flows into and fills the recess in the bottom of the piston and compresses the air so trapped to substantially full line pressure before the inertia of the piston and table is overcome. The piston then rises due to the air pressure, and because of its inertia it rises some distance above the port 29, thus allowing all the air to vent from beneath the piston, and permit the piston to drop suddenly and violently against the top of the jacket 21. This action is repeated continuously to give a jolting or vibrating table for tamping the concrete.

The piston 24 carries a table 35 which may either be cast solidly with the piston or formed separately and attached to the piston. The table carries a pair of molds 36, one on each of the machine. The molds are pivoted to the table by hinges 37, which permit the molds to swing from a normally vertical position in which the blocks are formed, shown in Fig. 5, to a reclined position in which the molds rest on brackets 38 on the frame 15, shown in Fig. 4. In the horizontal position the completed blocks may be removed from the forms or molds 36 and preferably placed in a drier.

50 The frame 15 has a frame 40 mounted on each side thereof at approximately the level of the table 35. As shown in Figs. 3, 4 and 6 the frames 40 support horizontal angle irons 42, which carry tracks 43. The tracks 43 guide a carriage 45, which is held on the tracks by a T-bar 46 bearing on the top of the carriage. Each carriage 45 has a pair of vertical posts 47 which carry one end of a core frame 49.

The core frame 49 has a guide 50 which operates on a track 51 fixed to the table 35. The outer end of the frame 49 comprises a vertical member which carries brackets 52. The brackets 52 embrace the posts 47 and slide thereon through a distance slightly greater than the 65 stroke of the piston 24. When the table 35 is in its lowermost position the guide 50 is horizontal. The frames 49 carry cores 55 which fit through corresponding holes 56 in the ends of the molds 36 as shown in Fig. 3. It will be noted that the guides 50 are slightly longer than the cores 55, which enables the cores to be completely withdrawn from the molds 36 while maintaining the guides 50 on the tracks 51. As shown in Fig. 3, the carriage 49 on one side of the frame rides on 70 one pair of parallel tracks 51 while the carriage 75

49 on the opposite side of the frame rides on an adjacent pair of parallel tracks 51.

The entire carriage 49, including the cores 55, vibrates with the table 35, entirely independently of the carriage 45.

The cores 55 are moved to and from their position in the molds 36 by fluid motors 59 each of which comprises a cylinder 60 closed at both ends, with a piston 61 operating therein. The pistons have piston rods 62 which pass through 10 packings in the outer ends of the cylinder and are connected to the carriages 45 in any suitable manner. The fluid motors 59 may be operated by the same air pressure source that operates the vibrator piston 24. The flow of air pressure 15 to either side of the piston 61 is controlled by a valve on the front of the machine.

The molds 36 are filled with concrete through a pair of hoppers 65 mounted one above each mold. The hoppers are connected by two bars 67 one at each end of the hoppers. A guide 68 composed of two angles back to back is mounted on each end of each hopper and operates on a track 70 to guide both hoppers simultaneously onto or away from the molds 36.

20 Deflectors 71 are mounted longitudinally in the hoppers to prevent the concrete from falling directly onto the cores 55 and bending them.

25 The hoppers are carried within a cradle, generally designated 75 and best shown in Fig. 7, 30 which has four parallel guides 76 each of which is composed preferably of a pair of angles back to back which guide the cradle in its vertical movement on tracks 77 fixed in the frame 15. The guides 76 are joined adjacent the top by 35 cross members 78-78. At the bottom of the cradle are a pair of angles 79 which run perpendicularly to the length of the hoppers, and which are adapted to engage the cross pieces 67 joining the hoppers to raise the hoppers with 40 the cradle. Suitable angles 80 join the angles 79 to complete the cradle. In its lowermost position the cradle 75 rests on a cross bar 81 which may be adjusted in elevation by the bolts 82.

45 A pair of knives 83 are mounted in the cradle 45 and lie on top of the inwardly projecting leg 84 of the angle 79. The knives are adapted to be moved outwardly between the molds 36 and the hoppers 65 to cut off the concrete above the top of the molds prior to withdrawing the 50 hoppers from the molds.

55 The knives 83 are each operated by a pair of racks 85 which are fixed to the knives and are engaged by pinions 86-86 or 87-87. It will be noted that the pinions 86-86 have a blank circumference intermediate the ends of the pinions in which there are no pinion teeth to permit the racks not actuated by that pinion to pass freely under it.

60 Both the pinions 86-86 and 87-87 are operated by double faced rack bars 90 in such a manner that when the bars are drawn up, the knives 83 are forced out to cut off the concrete between the hoppers and the molds.

65 Each of the rack bars 90 is guided by a pair of angles 91-91 back to back which are fastened to the frame 15. A filler 92 is fixed between each pair of angles 91-91 to hold the rack bar at the proper distance from the frame 15. The rack 70 bars 90 pass through holes in the angle 79 and are provided with lugs 93 at the lower ends, adapted to engage the angle 79 on the up stroke of the bar 90 and raise the cradle.

70 The rack bars are connected together by a pair 75

of bars 94 and braced by diagonal braces 95, as shown in Fig. 6.

5 A motor 96 which may be operated by compressed air is connected to the bars 94 through the piston rod 97 to raise the rack bars 90 and so force the knives outward and cut off the concrete at the top of the molds and then raise both the cradle and the hoppers off the molds.

10 A latch 98, best shown in Fig. 9, is provided in order to prevent the motor 96 from raising the hoppers before the knives 83 have completely cut off the concrete at the top of the molds. This latch is fixed in the frame 15 and includes a spring pressed plunger 99 which has a projection 15 100 with a cam surface 101 thereon. A cam follower 102 is provided on the bottom of the rack bar 90 to disengage the plunger 99 from its recess in the angle 79 when the knives 83 are in their outermost position.

20

Operation

In operation, the molds 36 are moved into upright position with the front plates clamped thereon. Compressed air is then admitted to the 25 outer ends of the cylinders 60 to move both the pistons 61 and the carriages 45 inwardly and insert the cores 55 through the apertures 56 and into place in the molds 36.

30 After the cores 55 are in place fluid pressure is admitted to the top of the fluid motor 96 to lower the double rack bars 90. The bars 90 lower the cradle 75 onto the cradle support 81 at which time the hoppers rest on the tops of the molds 36, with the knives 83 covering the bottoms of the 35 hoppers to prevent the passage of concrete into the molds.

35 Further downward movement of the rack bars 90 operates the pinions 86 and 87 which arcuate the rack bars 85 and draw the knives 83 inwardly onto the cradle 75 and thus open the bottoms of the hoppers 65 and permit the concrete in the hoppers to move down into the molds. Additional concrete is supplied to the hoppers from any convenient source, preferably through a 40 stationary supply hopper (not shown).

45 While concrete is being supplied to the molds 36 through the hoppers 65, air pressure is admitted through the hose 27 to the vibrator cylinder 23 to cause the table to vibrate or jolt in a manner heretofore described. The table 35 carries both the molds 36 and the hoppers 65 which 50 vibrate with the table 35.

55 When the knives are withdrawn from the hoppers 65 onto the cradle 75, the hoppers are free to vibrate with the molds 36 independently of the knives 83 which remain stationary during the vibration of the table.

60 The vibration or jolting of the molds 36 and the hoppers 65 tamps the concrete and forms it into a dense compact mass.

65 During the jolting or vibrating process concrete is kept in the hoppers 65 above the tops of the molds 36. The height at which the concrete must be maintained above the tops of the molds is determined by the weight and consistency of the concrete and by the distance through which the table drops, or the severity of the jolting.

70 The concrete must be as dry as possible in order that the blocks may be removed from the molds as soon as the jolting is completed. Any mechanical tamping of such dry concrete affects only the portion adjacent the tamper, and the effect of the tamping tapers off rapidly as the distance from the tamper increases. When such 75 concrete is jolted the weight of each particle of

concrete forms a tamper for the concrete beneath it. Since tamping affects only the concrete for a comparatively short distance below the tamper, when the concrete is jolted the tamping effect builds up to a maximum as the head increases 5 and remains constant for the remainder of the depth of the block.

7 The minimum height at which the concrete is maintained above the tops of the molds is, therefore, the height of concrete required to give the 10 maximum or uniform tamping effect for the particular concrete and jolting conditions. A smaller head or height of concrete produces a block 15 improperly tamped adjacent the top. A greater head, on the other hand, has no effect other than 20 to thoroughly tamp the concrete in the bottom of the hopper 65.

When the concrete is thoroughly tamped the vibration is stopped by manually cutting off the air supply to the vibrator 23-24. Air is then 25 admitted to the lower side of the fluid motor 96 which raises the double rack bars 90. During the raising of the rack bars 90, the cradle 75 is prevented from moving by the locks 98 which 30 hold the cradle in its lowermost position until released by the cam followers 102.

The rack bars 90 turn pinions 86 and 87 which 35 push the knives 83 outwardly, as best shown in Fig. 8, and cut off the excess concrete at the tops of the molds.

When the knives 83 are in their outermost position, the cam followers 102 release the latches 98, and the lugs 93 engage the angles 79 and lift the cradle 75. The tops of the angles 79 40 engage the bars 67 joining the hoppers 65 and move the hoppers up with the cradle 75.

The cores 55 may be withdrawn from the molds after the knives have cut off the concrete at the tops of the molds. The cores are withdrawn by supplying air to the inner ends of the cylinders 45 60, which moves out the pistons 61 and carriages 65 and 49 and withdraws the cores.

The molds 36 may then be turned down to a horizontal position, in which they rest on the brackets 38. The side of the mold resting on the 45 bracket 38 is then released and the remainder of the mold 36 is moved away from the released side and returned to its normal vertical position. The finished block which rests on the released side plate is removed therewith and preferably 50 placed in a drier until cured. A new side is placed in the mold and the cycle repeated.

55 It will be apparent that this invention is susceptible to various changes and modifications, and it is not, therefore, desired to limit it to the precise form herein shown and described but only by the scope of the appended claims.

What is claimed as new and desired to secure 60 by Letters Patent is:

1. A machine for molding concrete blocks or the like, comprising, a frame, a vibrator mounted in said frame, a table mounted in said frame and adapted to be vibrated by the vibrator, a 65 mold pivotally mounted on said table to vibrate therewith, said mold being rotatable with the finished block from a vertical molding position to a horizontal position in which the finished block may be removed, a feed hopper mounted in said frame and adapted to rest on said mold when in vertical position to vibrate therewith and to raise above said mold to permit the mold to pivot to horizontal position, means mounted on said frame to raise the hopper while permitting the hopper to vibrate independently of the 70 75

said means, and a knife carried by said means to cut off concrete at the top of the mold.

2. A machine for molding concrete blocks or the like, comprising, a frame, a vibrator mounted in said frame, a table mounted on said vibrator and adapted to be vibrated thereby, a mold carried by said table and vibrated therewith, a feed hopper mounted over said mold adapted to feed concrete into the mold, a cradle mounted in said frame independently of the vibrating portions of the machine, a knife mounted in said cradle and movable to a position between the mold and the hopper to sever the concrete therebetween, and means mounted in the frame to operate said knife.

3. A machine for making concrete blocks or the like, comprising, a frame, a vibrator mounted in said frame, a table carried in said frame and adapted to be vibrated by said vibrator, a mold pivotally mounted on said table to vibrate therewith, said mold being open on the top and rotatable on its pivot from its normal vertical position to a horizontal position, a feed hopper movably mounted in said frame adapted to vibrate with said mold and to move from a position on said mold to a position which will permit the mold to swing to its horizontal position, a cradle movably mounted in said frame engageable with the hopper to move the same off the mold, a knife carried in said cradle and movable to sever the concrete between the feed hopper and the mold, means to operate said knife, and means on said last named means engageable with said cradle to move said cradle and said hopper.

4. A machine for making concrete blocks or the like, comprising, a frame, a vibrator mounted in said frame, a table carried in said frame and adapted to be vibrated by said vibrator, a mold mounted on said table to be vibrated therewith, said mold having apertures therein to admit a core, a bracket mounted on said frame, a carriage movable on said bracket, a second carriage movable on said table, means connecting said carriages to permit vertical movement of said second carriage relative to the first, a core carried by said second carriage, and means to actuate said carriages to insert and withdraw the core from the mold.

5. A machine for making concrete blocks or the like, comprising, a frame, a vibrator mounted in said frame, a table carried in said frame and adapted to be vibrated by said vibrator, a mold carried by said table to vibrate therewith, a hopper mounted for movement onto and off said mold and adapted, when on said mold, to vibrate therewith, a cradle mounted to move in said frame independently of the vibrating members, means to move said cradle, and means on said cradle engageable with means on the hopper to raise and lower the hopper onto the mold.

6. A machine to mold concrete blocks, or the like, comprising, a frame, a vibrator mounted in said frame, a table mounted above said vibrator and adapted to be vibrated thereby, a mold pivotally mounted on said table to vibrate therewith when in vertical position and to pivot to a horizontal position in which the finished block may be removed, a hopper mounted to move vertically in said frame and to rest on said mold and be vibrated thereby, and to raise off said mold to permit the latter to pivot to its horizontal position, and means to operate said hopper.

7. A machine to mold concrete blocks, or the

like, as defined in claim 6 in which the last named means comprises a cradle mounted in said frame.

8. A machine to mold concrete blocks, or the like, comprising, a frame, a mold mounted in said frame, means in said frame to vibrate the mold independently of the frame, a cradle movable in said frame, a hopper mounted for movement onto and off said mold, means on said cradle engageable with means on the hopper to raise the hopper off the mold while permitting the hopper to vibrate independently of the cradle, and means to operate said cradle.

9. A machine to mold concrete blocks, or the like, as recited in claim 8, including a cut-off knife mounted in said cradle and operable upon conclusion of the vibration to sever the concrete between the mold and the hopper.

10. In a machine to make concrete blocks, or the like, a frame, a vibrator mounted in said frame, a mold mounted in said frame and adapted to be vibrated by said vibrator, a bracket mounted on said frame, a carriage mounted on said bracket, a plurality of cores adapted to move into and out of said mold, and means connecting said cores to said carriage, said means permitting the cores to vibrate with the mold independently of the carriage.

11. In a machine to make concrete blocks, or the like, a frame, a vibrator mounted in said frame, a mold mounted in said frame to be vibrated by said vibrator, a hopper mounted in said frame adapted to vibrate with said mold, a cradle mounted in said frame, means on said cradle engageable with means on the hopper to move the latter off the mold, a cut-off knife mounted in said cradle and adapted to sever the concrete between the hopper and the mold, means to actuate said knife, and means on said last named means engageable with the cradle to lift the latter.

12. A machine as recited in claim 11, including a lock mounted in said frame and engageable with said cradle to retain the cradle in its lowermost position until the knife has severed the concrete between the mold and the hopper.

13. A machine as recited in claim 11, including a lock mounted in said frame and engageable with said cradle to maintain the cradle in its lowermost position, and means mounted on said last named means to release the lock after the concrete has been severed between the hopper and the mold.

14. A machine as defined in claim 11, including a lock mounted in said frame and engageable with said cradle to maintain the cradle in its lowermost position, and a cam surface on said last named means engageable with said lock to release the cradle after the knife has completely severed the concrete between the mold and the hopper.

15. A machine to mold concrete blocks or the like, comprising, a frame, a table supported in said frame and adapted to vibrate therein, means to vibrate said table, a mold mounted on said table to vibrate therewith, a feed hopper mounted for movement onto and off said mold, and adapted to vibrate freely therewith when on said mold, a cut-off knife mounted in said frame independently of the vibrating portion thereof and adapted to cut off the concrete at the top of the mold after the block is formed, and means, including said knife to raise said hopper and the excess concrete therein off said mold.

16. A machine to mold concrete blocks or the

like, comprising, a frame, a table supported in said frame and adapted to vibrate therein, means to vibrate said table, a mold mounted on said table to vibrate therewith, a feed hopper mounted for movement onto and off said mold, and adapted to vibrate freely therewith when on said mold, a cut-off knife mounted in said frame and adapted to cut off the concrete at the top of the mold after the block is formed, and means, including said knife to raise said hopper and the excess concrete therein off said mold.

17. A machine for making concrete blocks or the like, comprising, a frame, a vibrator mounted in said frame, a table carried in said frame and adapted to be vibrated by said vibrator, a mold having an aperture therein mounted on said table to vibrate therewith, a feed hopper mounted above said mold to vibrate therewith, a bracket mounted on said frame, a carriage mounted on said bracket, a second carriage movable on said table, means connecting said carriages to permit vertical movement of said second carriage relative to the first carriage, a core carried by said second carriage, and means to actuate said carriages to insert the core into the mold through the aperture therein.

18. A machine for making concrete blocks or the like, comprising, a frame, a vibrator mounted in said frame, a table carried in said frame and adapted to be vibrated by said vibrator, a mold having an aperture therein mounted on said table to vibrate therewith, a feed hopper mounted above said mold to vibrate therewith, a knife carried in said frame and insertable between the hopper and the mold to sever the concrete therebetween, a bracket mounted on said frame, a carriage mounted on said bracket, a second carriage movable on said table, means connecting said carriages to permit vertical movement of said second carriage relative to the first carriage, a core carried by said second carriage, and means to actuate said carriages to insert the core into the mold through the aperture therein.

19. A machine for making concrete blocks or the like, comprising, a frame, a vibrator mounted in said frame, a table carried in said frame and adapted to be vibrated by said vibrator, a mold having an aperture therein mounted on said table to vibrate therewith, a feed hopper mounted above said mold to vibrate therewith, a knife carried in said frame and insertable between the hopper and the mold to sever the concrete therebetween, means, including said knife, to raise the hopper and the excess concrete therein off the mold, a bracket mounted on said frame, a carriage mounted on said bracket, a second carriage movable on said table, means connecting said carriages to permit vertical movement of said second carriage relative to the first carriage, a core carried by said second carriage, and means to actuate said carriages to insert the core into the mold through the aperture therein.

20. A machine for making concrete blocks or the like, comprising, a frame, a vibrator mounted in said frame, a table carried in said frame and adapted to be vibrated by said vibrator, a mold carried by said table to vibrate therewith, a hopper mounted for movement onto and off said mold and adapted, when on said mold, to vibrate therewith, a cradle mounted in said frame independent of the vibrating portions of the machine, a knife carried by said cradle and adapted to pass between the hopper and the mold to sever the concrete therebetween, means to move

said cradle, and means on said cradle including said knife engageable with said hopper to raise the hopper and the excess concrete therein.

21. A machine for making concrete blocks or the like, comprising, a frame, a vibrator mounted in said frame, a table carried in said frame and adapted to be vibrated by said vibrator, a mold carried by said table to vibrate therewith, a hopper mounted for movement onto and off said mold and adapted, when on said mold, to vibrate therewith, a cradle mounted in said frame independently of the vibrating members, a knife mounted in said cradle, means to actuate said knife to cut off the concrete at the top of the mold, and means on said last named means to raise the cradle and hopper.

22. A machine as defined in claim 21 including means to hold the cradle in its lowermost position until after the knife has completely severed the concrete.

23. A machine for making concrete blocks or the like, comprising, a frame, a vibrator mounted in said frame, a table carried in said frame and adapted to be vibrated by said vibrator, a mold mounted on said table to vibrate therewith, a feed hopper movably mounted in said frame adapted to vibrate with said mold, a cradle movably mounted in said frame engageable with the hopper to move the same off the mold, a knife carried in said cradle and movable to sever the concrete between the feed hopper and the mold, means to operate said knife, and means on said last named means engageable with said cradle to move said cradle and said hopper.

24. A machine for making concrete blocks or the like, comprising, a frame, a mold mounted in said frame, a hopper movable onto and off said mold, a cradle engageable with a portion of said hopper to lift the hopper off the mold, a knife mounted in said cradle, means to operate said knife to cut off the concrete between the mold and the hopper, a latch engageable with a portion of said cradle, and means to release said latch to permit the cradle to rise after the knife has completely severed the concrete between the hopper and the mold.

25. A machine for making concrete blocks or the like comprising, a frame, a mold mounted in said frame, a hopper movable onto and off said mold, a cradle engageable with a portion of said hopper to lift the hopper off the mold, a knife mounted in said cradle, a rack bar fixed on said knife, a pinion engageable with said rack bar, a second rack bar mounted substantially vertically and engageable with said pinion to actuate said knife, said rack bars and said pinion being so arranged that upward movement of the second rack bar moves the knife outwardly to sever the concrete between the hopper and the mold, a latch engageable with a portion of said cradle, and means on said second rack bar to disengage said latch and permit the cradle to be raised after the knife has completely severed the concrete between the mold and the hopper.

26. A machine for making concrete blocks or the like comprising, a frame, a mold mounted in said frame, a hopper movable onto and off said mold, a cradle engageable with a portion of said hopper to lift the hopper off the mold, a knife mounted in said cradle, a rack bar fixed on said knife, a pinion engageable with said rack bar, a second rack bar mounted substantially vertically and engageable with said pinion to actuate said knife, said rack bars and said pinion being so arranged that upward movement of

- the second rack bar moves the knife outwardly to sever the concrete between the hopper and the mold, a spring pressed latch engageable with a portion of said cradle, and a cam on said second rack bar to disengage said latch against the action of said spring and permit the cradle to be raised after the knife has completely severed the concrete between the mold and the hopper.
- 10 27. A machine for making concrete blocks or the like comprising, a frame, a mold mounted in said frame, a hopper movable onto and off said mold, a cradle engageable with a portion of said hopper to lift the hopper off the mold, a knife mounted in said cradle, a rack bar fixed on said knife, a pinion engageable with said rack bar, a second rack bar mounted substantially vertically and engageable with said pinion to actuate said knife, said rack bars and said pinion being so arranged that upward movement of the second rack bar moves the knife outwardly to sever the concrete between the hopper and the mold, a latch engageable with a portion of said cradle, means on said second rack bar to disengage said latch, and a member formed on said second rack bar engageable with said cradle after release of said latch to raise the cradle.
- 15 28. A machine for making concrete blocks or the like comprising, a frame, a mold mounted in said frame, a hopper movable onto and off said mold, a cradle engageable with a portion of said hopper to lift the hopper off the mold, a knife mounted for horizontal movement in said cradle, a pair of horizontal rack bars, one of said rack bars being fixed on each end of said knife, a pair of pinions mounted in said cradle and engageable with said rack bars, a second pair of rack bars mounted for substantially vertical movement in said frame and engageable with
- 20 40 said pinions to actuate the knife outwardly upon upward movement thereof to sever the concrete between the hopper and the mold, means to actuate said second pair of rack bars simultaneously, a latch engageable with a portion of the cradle, and means on one of said rack bars to disengage said latch and permit the cradle to be raised after the knife has completely severed the concrete between the hopper and the mold, and means on each of said second rack bars engageable with said cradle after said last named means has released said latch to raise said cradle.
- 25 30. A machine for making concrete blocks or the like comprising, a frame, a mold mounted in said frame, a hopper mounted in said frame and movable onto and off said mold, a cradle engageable with a portion of said hopper to lift the same off the mold, a knife mounted in the cradle, means to actuate the knife to cut off the concrete between the mold and the hopper, a latch engageable with a portion of said cradle when in lowered position, and means on the knife actuating means engageable with said latch after the knife has completed the cut between the hopper and the mold to release the latch and permit the cradle to raise the hopper off the mold.
- 30 45 31. A machine for making concrete blocks or the like comprising, a frame, a mold mounted in said frame, a hopper movable onto and off said mold, a cradle engageable with a portion of said hopper to lift the hopper off the mold, a knife mounted in said cradle, means to operate said knife to cut off the concrete between the hopper and the mold, a latch engageable with a portion of said cradle when in lowered position, means on the knife actuating means to release said latch after said knife has completely severed the concrete between the hopper and the mold, and means on said knife actuating means to raise the cradle after the release of the latch.
- 40 45 50

FREDERICK W. PFEIFER.
